UNITED STATES PATENT OFFICE.

WILLIAM MILBRATH, OF LAKEFIELD, MINNESOTA, ASSIGNOR OF ONE-TENTH TO
SAMUEL DUBETZ, OF ST. PAUL, MINNESOTA.

STORM WINDOW.

Application filed March 28, 1923. Serial No. 628,205.

To all whom it may concern:

Be it known that I, WILLIAM MILBRATH, a citizen of the United States, residing at Lakefield, in the county of Jackson and

5 State of Minnesota, have invented certain new and useful Improvements in Storm Windows; and I do hereby declare the following to be a full, clear, and exact description of the invention, such as will enable 10 others skilled in the art to which it appertains to make and use the same.

This invention relates to a window structure and particularly to a storm window. Such storm windows or outside windows 15 are now commonly used in the Northwest and other colder portions of the country. The window commonly used comprises a sash having therein one or more panes, which sash is of a size fitting the window casing so that the storm sash is substantially the same size as the window casing. With this structure the storm window must always be placed in position from the outside and it is necessary to use ladders or scaffolding 20 for the window in the upper stories. It is often necessary also to place the storm windows during bad weather so that it is quite inconvenient work on the outside of the building.

30 It is an object of this invention, therefore, to provide a storm window of simple and efficient construction which can easily and quickly be placed in position from the interior of the building or window casing.

35 It is a further object of the invention to provide such a storm window composed of upper and lower sections, which sections can be moved through the sash openings of the window casing with the ordinary sash in 40 the casing, together with means for holding said sections in position.

It is still another object of the invention to provide a storm window comprising the upper and lower sections, the upper section 45 having hinges thereon and the lower section interlocking with the upper section for swinging movement relative thereto, and carrying means detachably engaging the hinges on said upper section. It is a still 50 further object of the invention to provide novel and efficient means for holding the

sections in place and for holding the lower section locked in position and in various positions of adjustment.

These and other objects and advantages 55 of the invention will be fully set forth in the following description made in connection with the accompanying drawings in which like reference characters refer to the same parts throughout the different views, and in 60 which,

Fig. 1 is a view in front elevation of the window casing showing a storm window in position as viewed from the inside;

Fig. 2 is a vertical section taken on the 65 line 2—2 of Fig. 1;

Fig. 3 is a view in front elevation showing the window casing and storm window in place as viewed from the outside;

Fig. 4 is a fragmentary section taken on 70 the line 4—4 of Fig. 1 and shown on an enlarged scale; and

Fig. 5 is a horizontal section taken on the line 5—5 of Fig. 1.

Referring to the drawings, an ordinary 75 window frame or casing is shown comprising side members 1, a bottom sill 2 and a top cross member 3 and the usual upper and lower sliding sash 1^a and 2^a, respectively. The outer bead or strip of the casing which 80

extends along the sides and across the top thereof adjacent its outer side is shown as 4. The storm window comprising the present invention includes an upper section or sash 5 adapted to fit in the window casing 85 and against the outside of the bead or strip 4 and a lower section 6 also adapted to fit against said bead. The top portion of the bead 4 has projecting downwardly therefrom at spaced points somewhat adjacent 90

its side portions, pins 7, and the top portion of the upper section 5 has small angle brackets 8 secured to the inside thereof, the top plates of which are apertured to receive the pins 7 to prevent outward movement of 95

this portion of the section. The bead or strip 4 also has projecting inward therefrom at intermediate points the pins 9 and these pins are adapted to project into slots 10 formed in U-shaped brackets 11 secured to 100

the front sides of the section 5 adjacent its lower edge. Each bracket 11 has pivoted

thereto a lever 12 which is channel-shaped or, in other words, U-shaped in cross section with the open side of the channel directed outwardly toward the window jamb and 5 adapted to swing into the channel or U-shaped part of the bracket 11 on each side of the pin 9 and lock the section 5 securely in position at its lower portion. The sides of the members 12 are inclined toward each 10 other toward their outer or free edges so that the same bind against the sides of the bracket 11 and snugly fit the pin 9 whereby a clamping action is obtained and a locking device formed having no free movement so 15 that there will be no rattling thereof. The upper section 5 has secured at the bottom of its side portions on the outside thereof, hinges 13 which have their lower butts or flanges provided with slots 14, which slots, 20 at their upper portions have parallel sides 14^a which curve outwardly at their lower edges. The upper sash is also preferably provided with a semi-circular groove 15 extending across its bottom edge and the lower 25 section or sash 6 is provided with a corresponding rib adapted to fit in such groove. Said lower section also has secured in its side portions adjacent the top thereof bolts 16. Said bolts have heads at their outer 30 portions illustrated as of rounded or button-head type and square shanks adjacent said heads. Said shanks each extend through a square hole formed in a plate 17 secured to the outside of the section and the inner and 35 threaded portion of the bolt extends through a rounded hole in a plate 18 screwed to the inside of the sash. The squared portion 19 of the bolt is contacted by a coiled spring 20 surrounding the bolt and disposed in a 40 recess formed in said sash, said spring contacting the plate 18 at its inner side. It will thus be seen that the spring 20 tends to push the head 16 of the bolt outward from the sash, this movement being limited by 45 the clamping wing nut 21 threaded onto the bolt at the inside of the plate 18. The squared portion 19 of the bolt is adapted to fit in the slot 14 of each of the hinges 13 and the lower section will thus be hingedly 50 connected to the upper section, the nut 21 being securely tightened to hold the sections in this position. The lower section 6 has secured to one of its side portions adjacent its lower edge a small bracket 22 having projecting ears between which is pivoted the 55 end of a locking arm 23, which arm for its major portion, is of angular shape in cross section, and has one flange provided with spaced notches 24, which notches are adapted 60 to be individually engaged over a screw head 25 projecting from the bead 4 adjacent its bottom portion whereby the lower section may be held in various open positions. When the lower section is swung to tightly 65 closed position, the arm 23 will be swung

upwardly to lie along the side edge of the section and a small swinging member 26 is pivoted to the side of the section above the end of said arm, which member is of angle shape in cross section and one side of which 70 is adapted to swing over the upper end of the arm 23. A plate 27 of angle shape in cross section is secured to the bead 4 so as to have one side thereof projecting between the arm 23 and the front side of the member 75 6. This plate causes the arm 23 to incline toward the inside of the casing and the upper end of said arm must be pushed tight against the plate 27 and sprung slightly to be engaged by the swinging member 26. This 80 tight springing engagement causes the members to be held tightly and securely in position and prevents any tendency of the same to rattle. The section 6 is also provided at its other front side adjacent the bottom 85 thereof with a plate 11 and lever 12, similar to these parts described in connection with the upper section 5, which parts co-operate with another pin 9 projecting inwardly from the bead 4. The lower section is also provided at each front side somewhat adjacent the top with swinging bail-shaped handles 28 having their ends extending through angle plates 29 secured to said sash. 90

With the parts as shown and described, 95 when it is desired to place the storm window in position, the usual upper sash 1^a of the window will be lowered. The upper section 5 can then be passed through the sash opening and the holes in the brackets 8 engaged over the pins 7. The lower part of the section will then be swung inwardly so that the brackets 11 engage over the pins 9. The levers 12 will then be swung to locking position and the upper section will be held in place. The usual lower sash 2^a of the window can now be raised and the lower section 6 passed through the lower sash opening. The nuts 21 will be loosened and the heads 16 will therefore be projected beyond the plate 17. The section can now be held by the handles 28 and the squared sections 19 of the bolts slid upwardly into slots 14 of the hinges 13 and the top portion of the section 6 brought into close engagement 100 with the groove 15 of the upper section. The wing nuts 21 will now be tightened and the lower section will thus be firmly clamped and secured to the hinges on the upper section. The springs 20 will assist in holding the bolts in firmly clamped position so there will be no tendency of the nuts 21 to work loose. The lower part of the section 6 can now be swung inwardly to closed position 105 and locked in tightly closed position by the parts 23 and 26 as well as the parts 9, 11 and 12, or said window can be placed in the desired open position by engagement of one of the notches 24 over the headed screw or bolt 110 25. The storm window is thus easily and 115 120 125 130

- quickly installed from the inside of a building and will remain securely in position as long as desired. The lower section 6 can at any time be opened or closed for ventilating purposes. It will be obvious that sections of the window also may be taken down with the same ease and rapidity with which they were put up by merely reversing the operations above described.

5 From the above description it will be seen that applicant has invented an inexpensive, simple and efficient storm window structure. With such a such a structure, the serious objection of placing the storm windows 10 from the exterior of the building is overcome. The storm window can be easily and quickly placed in position by any person and it will not be necessary to wait for the services of a carpenter or other mechanic 15 who must use a ladder or scaffolding to place the windows. If desired, the adjustable arms 23 may be placed on each side of the window to hold the same in its various open positions. It will be seen that by the 20 provision of the semicircular groove 15 and the part fitting therein that the sections can readily swing through the desired angle relative to each other and that a very tight 25 joint is provided which will effectively prevent the passage of air.

30 It will, of course, be understood, that various changes may be made in the form, details, arrangement and proportions of the parts without departing from the scope of 35 applicant's invention, which, generally, stated, consists in a device capable of carrying out the objects enumerated and as shown and described and set forth in the appended claims.

40 What is claimed is:

  1. A storm sash for a sliding sash window structure, comprising an upper section insertable in the window frame of said structure through the opening therein from the inner side thereof without removing the sliding sash, and means operable from said inner side for removably retaining said section in position, a lower section likewise insertable through the window opening, and means operable from the inner side of the window structure for detachably hinging said lower section and said upper section.
  2. A storm sash for a sliding sash window structure, comprising an upper section insertable in the window frame of said structure through the opening therein from the inner side thereof without removing the sliding sash, and means operable from said inner side for removably retaining said section in position, a lower section likewise insertable through the window opening, hinges comprising pivotally connected parts on said upper section, means on said lower section adapted to detachably engage said hinges to connect said sections, and means for holding

45 said lower section in closed position or in various open positions.

3. A storm sash for a sliding sash window structure, comprising an upper section insertable in the window frame of said structure through the opening therein from the inner side thereof without removing the sliding sash, and means operable from said inner side for removably retaining said section in position, a lower section likewise insertable through the window opening, hinges comprising pivotally connected members permanently secured to one of said sections, and means on the other section detachably engaging said hinges and adapted to be clamped thereto to connect said sections.

4. The combination with a window casing of a storm window comprising an upper section, means at the top part of said casing engaged by said section, means at the intermediate part of said casing engaged by said section for locking said section in position, a lower section normally having detachable interlocking engagement with said upper section permitting swinging movement thereof, means on said casing engaged by means on said lower section for holding said section in position, hinges secured to one of said sections, and means on the other of said sections detachably engaging said hinges and adapted to be clamped thereto swingingly to connect said section.

5. The combination with the window casing of a storm window comprising an upper section, spaced pins projecting from the top of said casing plates at the upper portion of said section engaging said pins, members projecting inwardly of said casing at an intermediate part thereof, means on said section engaging said members for holding said section in position, the lower section having its upper edge arranged to fit in the lower edge of said upper section, retaining means projecting inwardly from said casing, means on said lower section adapted to engage said last named means for holding said section in closed or open position, hinges secured to one of said sections and having slotted flanges projecting toward the other section, and means on said latter section adapted to be disposed in said slotted flanges and to be clamped thereto swingingly to connect said sections.

6. A storm window comprising upper and lower sections, hinge permanently secured to one of said sections and having slotted flanges projecting toward said other section, a headed bolt carried by said latter section and having a portion adjacent said head adapted to be disposed in said slotted flange, means in the section carrying said bolt for projecting said head at the side thereof and clamping means engaging said bolt to clamp the same to said hinge.

7. A storm window comprising upper and lower sections fitted together for relative swinging movement, a hinge carried by one of said sections having a slotted flange projecting toward the other section, a headed bolt carried by said latter section and extending transversely therethrough having an angular section adjacent its head adapted to be disposed in said slotted flange, a spring

disposed about said bolt tending to project 10 said head at the side of said section, and a clamping nut at the inside of said section engaging said bolt for clamping the same to said slotted flange swingingly to connect said sections.

In testimony whereof I affix my signature.

WILLIAM MILBRATH.
